UNITED STATES PATENT OFFICE.

HERVEY D. GANSE, OF LAKE VIEW, ILLINOIS.

DEVICE FOR OPERATING A SET OF LEVERS.

SPECIFICATION forming part of Letters Patent No. 331,629, dated December 1, 1885.

Application filed December 10, 1883. Serial No. 114,020. (No model.)

To all whom it may concern:

Be it known that I, HERVEY D. GANSE, formerly of St. Louis, and now of Lake View, Cook county, Illinois, have made a new and 5 useful Improvement in Devices for Operating a Set of Levers, of which the following is a full, clear, and exact description, reference being had to the annexed drawings, making part of this specification, in which—

10 Figure 1 is a vertical longitudinal section of the device, the parts being as when the keys are not depressed; Fig. 2, a similar section, the keys being depressed slightly, and so as to bring the blocks into line; Fig. 3, a similar 15 section, the keys being depressed still farther, and so as to cause the line of blocks to be moved; Fig. 4, a top view showing a portion of one side of the device; Fig. 5, a vertical transverse section on the line 5 5 of Fig. 3, 20 the uprights of the keys not being shown; and Figs. 6, 7, 8, 9, 10, details, being views of files of blocks, the blocks in the various figures being variously arranged, and in Figs. 9, 10 being differently shaped. Fig. 11 is a plan of 25 the device. Fig. 12 is a side elevation, and Fig. 13 is a front elevation.

The same letters of reference denote the same parts.

The present invention relates to a mode of 30 moving any one, as desired, of a set of levers by means of one or more of another set of levers, the levers of the operating set being less in number than those of the set operated upon.

35 $A' A^2$, &c., represent the set of operating-levers. Saving that these levers are less in number than the levers operated upon, I do not wish to be confined to any particular number thereof. Each of the levers A' , &c., 40 can be similarly and independently vibrated, as indicated by the broken lines a , Fig. 1, the pressure of the operator's hand causing the lever to be depressed, and any suitable means—such as a spring, (not shown)—operating to 45 restore the lever to its original position when the operator's hand is removed.

The levers A' , &c., may be considered, and hereinafter will be styled, "keys," as the operator's hand is applied to them as to the key-board of a piano. Each key has a corresponding frame, $B' B^2$, &c., whose movement is responsive to that of the key—that is, each

frame, at its forward ends, b , is pivoted at b' to the side c of the frame C of the device, so that the rear end, b^2 , of the frame can be lowered and elevated, as indicated in Figs. 2 and 1, respectively. The shape of these frames is shown in Figs. 1, 2, 3, 4, 5—that is, at each side of the key-board from the pivots $b' b^2$ the frame extends rearwardly, and then, at b^2 , across 6c and above the keys. Each key A' , &c., is provided with an upright, a' , and each frame B' , &c., with a corresponding arm, b^3 , so that when the keys A' , &c., are not depressed their respective uprights a' , &c., come beneath the corresponding arms, b^3 , &c., and thereby uphold the frames B' , &c. On depressing any key its corresponding frame drops, and when two or more of the keys are depressed two or more of the frames drop. 70 In Fig. 1, as stated, all of the frames $B' B^2$, &c., are upheld. In Fig. 2, five, $B^2 B^3 B^4 B^5$ 75 B^6 , of the frames are shown down.

$D' D^2 D^3 D^4 D^5 D^6$ represent what may be styled a "set" or "file" of blocks. But one file 80 of these blocks is shown in the drawings; but there are as many files as there are levers to be moved. The files are arranged parallel with each other, and they extend longitudinally in the device. The several blocks in each file are connected, respectively, with the frames $B' B^2 B^3 B^4 B^5 B^6$. Therefore, when any one of the frames is dropped, all the blocks connected with that frame drop with the frame, and if two frames are dropped all the blocks 85 connected with those two frames throughout the entire series of files drop with those two frames, and so on. The preferable mode of connecting the blocks is to extend the block in the form of or provide it with an arm, d , which, 90 at d' , is jointed to the frame. This enables the blocks, after being lowered, to be moved, as indicated in Figs. 2 and 3, respectively.

In order to move any particular lever of the set of levers operated upon, the particular 95 file of blocks belonging to that lever must be brought into line, as shown in Fig. 2. The keys A' , &c., are then depressed farther, and the entire file of blocks thereby moved endwise in a rearward direction, as shown in Fig. 100 3. The file in its movement encounters a lever, E , which is pivoted at e to a cross-bar, c' , and extended upward at e' . Each of the levers F (but one shown in drawings) to be

operated upon has a corresponding lever, E, the free end *f* of the lever F coming in front of the extension *e'*, as shown in Fig. 1. The movement of the file, therefore, causes the lever E to tilt on its pivot *e*, and to throw the end *f* of the lever F forward. The end *f* is provided with a projection, *f'*, which in the movement of the lever F comes beneath the rear end or cross-bar *g* of an oscillating frame, 5 G, and by continuing to depress the keys A', &c., the bar *g* is caused to descend and draw down with it the lever F, as indicated by the broken lines in Fig. 1. The frame G is pivoted at *g'* to the sides *c c* of the frame C, 10 and is provided with a stirrup, *g''*, whose cross-bar *g''* passes beneath the key-board A', &c., and so that when one or more of the keys are depressed they shall encounter and bear down with them the cross-bar *g''*. This causes the 15 rearward end of the frame G to move downward and effect the movement of the lever F, as described. A spring, *g'*, acts to restore the frame G when the keys A', &c., are released.

20 25 The preferable mode of communicating the motion of the keys to the files of blocks is as follows: H represents a bar extending across the device in front of the forward ends of the files and adapted to be moved against the files, and thereby to move them endwise. To this end the bar H is supported in the position described by means of the arms *h h*, which in turn are pivoted at *h'* to the base *c''* of the device. Each key A', &c., is provided with an 25 arm, *a''*, which extends upward in front of the bar H, and opposite the bar, having an incline, *a''*. When a key is depressed, its incline *a''* comes against the bar H and presses it against the files. The bar H is preferably not allowed to 30 come directly against the front blocks of the files. In front of each file is a movable block, D', which is pivoted by means of the arm *d'* to the fixed bar D''. The bar H moves this block D', and the block D' in turn moves the 35 file. To move any desired lever F, the blocks of the file belonging to that lever must, as stated, be brought into line. Therefore as many keys A', &c., and frames B', &c., must be depressed as there are blocks in that file 40 out of line in order to effect the movement of the lever; but the various blocks throughout all the files must be connected with the frames, so that when any key or combination of keys is struck in order to bring the blocks in 45 one file into line the blocks in all the other files respectively shall not be brought into line, and in consequence no other lever F shall be then moved. To this end the arms *d*, which connect the blocks with the frames, 50 are of various lengths, and it may be stated, generally, the principle upon which the blocks D', &c., in the present construction are combined with each other and with the other parts of the device and operated and upon 55 which the keys are combined and operated 60 65

is similar to that upon which the wedges and keys in a pending application of mine filed July 18, 1883, and numbered serially 101,233, (to which reference for convenience is hereby made,) for Letters Patent upon an analogous device are combined and operated, the chief difference being that in the construction referred to the wedges as they are moved into line exert a wedging action, while in the present construction the blocks are first brought 75 into line, and then, after the blocks in the file are in line, the file as one part is moved endwise.

The blocks D', &c., may, as indicated in Figs. 1, 9, and 10, be variously shaped without departing from the principle of the improvement. Figs. 6, 7, 8, 9, 10 also illustrate how the blocks may in operating the device be variously relatively placed. The various files of blocks work in suitable guides, D'. 85

I claim—

1. The combination of the bar H, the blocks D' D'', &c., and the lever E, as described.

2. The combination of the file of blocks D' D'', &c., and the lever E, as described. 90

3. The combination of the file of blocks D' D'', &c., the lever E, and the lever F, as described.

4. The combination of the lever E, the lever F, and the frame G, as described. 95

5. The combination of the file of blocks D' D'', &c., the levers E F, and the frame G, as described.

6. The combination of the key A', the arm *a''*, the bar H, and the file of blocks D' D'', &c., 100 as described.

7. The combination of the bar H, the block D', and the file of blocks D' D'', &c., as described.

8. The combination of a file of blocks, D' D'', &c., a movable part to press against, and a movable part to be pressed by the file when the blocks are in line, substantially as described. 105

9. The combination of a file of blocks, D' D'', &c., a movable part to press against the file, a movable part, substantially as described, to be pressed by the file when the blocks are in line, and means, substantially as described, for moving the blocks of the file into line. 115

10. The combination of a series of files of blocks, D' D'', &c., a bar, H, adapted to be moved against the files, and a series of movable parts to be moved, respectively, by the files as the blocks of the files respectively come 120 into line, substantially as described.

11. The combination of a file of blocks, D' D'', &c., and the frames B' B'', &c., said blocks being connected with said frames by means of connections of different lengths, as and for the 125 purpose described.

HERVEY D. GANSE.
